[57] **CLAIM**

The ornamental design for a three-way detector rack, as shown.

DESCRIPTION

FIG. 1 is a perspective view of a three-way call detector rack showing my new design;

FIG. 2 is a front elevational view of the three-way call detector rack;

FIG. 3 is a rear elevational view of the three-way call detector rack;

FIG. 4 is a right-hand side elevational view of the three-way call detector rack; and

FIG. 5 is a left-hand side elevational view of three-way call detector rack;

FIG. 6 is a top plan view of the three-way call detector rack; and,

FIG. 7 is a bottom view of the three-way call detector rack.

FIG.1

FIG. 2

FIG.3

FIG.4

FIG.5
